(57) **CLAIM**

The ornamental design for a radiation shielding container lid, as shown and described.

DESCRIPTION

FIG. 1 is a perspective view of a radiation shielding container lid in accordance with a first embodiment of the present invention.

FIG. 2 is a front view of the radiation shielding container lid shown in FIG. 1.

FIG. 3 is a rear view of the radiation shielding container lid shown in FIG. 1.

FIG. 4 is a right side view of the radiation shielding container lid shown in FIG. 1.

FIG. 5 is a left side view of the radiation shielding container lid shown in FIG. 1.

FIG. 6 is a top view of the radiation shielding container lid shown in FIG. 1.

FIG. 7 is a bottom view of the radiation shielding container lid shown in FIG. 1.

FIG. 8 is a perspective view of a radiation shielding container lid in accordance with a second embodiment of the present invention.

FIG. 9 is a front view of the radiation shielding container lid shown in FIG. 8.

FIG. 10 is a rear view of the radiation shielding container lid shown in FIG. 8.

FIG. 11 is a right side view of the radiation shielding container lid shown in FIG. 8, the left side view being a mirror image thereof; and,

FIG. 12 is a top view of the radiation shielding container lid shown in FIG. 8, the bottom view of the second embodiment being the same as that shown in FIG. 7.

Features shown in broken lines form no part of the claimed design.
